H. L. BEARD.
APPARATUS FOR USE IN THE TREATMENT OF PILES.
APPLICATION FILED OCT. 10, 1917.

1,258,979.

Patented Mar. 12, 1918.

Inventor

H. L. BEARD

By Watson E. Coleman

Attorney

UNITED STATES PATENT OFFICE.

HARRY L. BEARD, OF QUINCY, ILLINOIS.

APPARATUS FOR USE IN THE TREATMENT OF PILES.

1,258,979.

Specification of Letters Patent. Patented Mar. 12, 1918.

Application filed October 10, 1917. Serial No. 195,772.

To all whom it may concern:

Be it known that I, HARRY L. BEARD, a citizen of the United States, residing at Quincy, in the county of Adams and State 5 of Illinois, have invented certain new and useful Improvements in Apparatus for Use in the Treatment of Piles, of which the following is a specification, reference being had to the accompanying drawings.

- 10 This invention relates to an apparatus for use in treating piles, and has for its primary object to provide simple means which may be applied to the affected parts for the application of a medicament thereto.
- 15 It is also an object of my invention to provide a pad and suitable harness for retaining the same in position, and medicament receiving means adapted for detachable connection to said pad, and for insertion 20 into the rectum, said means being acted upon by the muscles, so that the medicament will be expelled and applied to the affected parts.

It is another object of the invention to 25 provide improved means for holding the medicament containing and releasing instrument within the rectum, and which will also prevent the protrusion of the piles or hemorrhoids.

30 And it is a further general object of my invention to provide a device for the purpose above stated, which is simple and inexpensive in its construction and also highly serviceable and convenient in practical use.

35 With the above and other objects in view, my invention consists in the novel features of construction, combination, and arrangement of parts to be hereinafter more fully described, claimed and illustrated in the accompanying drawing, in which:

Figure 1 is a perspective view illustrating the device as applied in practical use;

Fig. 2 is a sectional view through the compressible medicament containing nipple and 45 the pad or base to which it is connected; and

Fig. 3 is a perspective view of the nipple.

Referring in detail to the drawing, 5 designates a relatively heavy piece of fabric 50 constituting the base of the pad or bandage. This pad base may be of any desired form in plan, but is preferably of substantially rectangular shape. Upon one side of this base 5, a sheet of rubber, indicated at 6, is 55 secured. This rubber sheet is provided with a central opening and slits extending dia-

metrically from this opening to provide a series of tabs or lips, indicated at 7.

A nipple 8 of soft rubber is provided with a circular base 9, which is adapted to be inserted through the central opening in the rubber sheet and detachably held in place upon the pad or bandage by the several tabs or lips 7. The nipple at its other end is open, as shown at 10, and the elongated body 60 of the nipple is also provided in the wall thereof with a plurality of perforations 11.

12 designates a waist band, which is adapted to be buckled or otherwise secured around the waist of the user, as shown, and 70 a strap 13 is secured to one end of the pad or bandage and is adapted to be connected at its free end to a buckle on the back portion of the waist band. Additional straps or tapes 14 are also secured to the other end 75 of the pad or bandage 5 adjacent its opposite edges and are adapted to extend upwardly between the legs and be connected to additional buckles or fastening means on the band 12. These straps 13 and 14 are 80 preferably of elastic material.

In the use of the invention, it will be understood that the nipple 8 is first filled with a suitable ointment or medicament, and the base 9 of this nipple is then engaged under 85 the tabs or lips 7 on the pad. The waist band is secured around the waist and the nipple then inserted into the rectum. The straps or tapes 14 are finally drawn upwardly and connected to the band 12 and 90 properly adjusted so that the pad will be tightly held in its applied position. The nipple will be compressed or squeezed in the action of the muscles of the rectum when it is inserted, thereby causing the expulsion 95 of the ointment contained in the nipple through the opening 10 in the end thereof and the perforations 11. The muscles are thus kept thoroughly lubricated in a manner to assist in the natural actions of the rectum so that constipation will be prevented. The ointment has a healing action upon the parts and the bandage carrying the nipple effectively prevents the protrusion of the piles from the rectum.

100 From the foregoing description, taken in connection with the accompanying drawing, the construction, manner of use and several advantages of the device will be clearly understood. By applying the ointment or 110 medicament directly upon the affected parts in the manner explained, a complete cure is

greatly expedited. The device may be very easily and quickly applied by the user or removed, when necessary. In view of the very simple form and construction of the 5 several parts of the device, it will also be obvious that the invention can be produced at relatively small manufacturing cost.

While I have herein shown and described the preferred construction and arrangement 10 of the several features of the device, it is to be understood that the same are susceptible of considerable modification and I, therefore, reserve the privilege of adopting all such legitimate changes as may be fairly 15 embodied within the spirit and scope of the invention as claimed.

Having thus fully described my invention, what I claim is:—

1. An apparatus of the character described 20 including a compressible medicament containing nipple having perforated body walls for the extension of the medicament upon compression of the nipple, said nipple having an enlarged flat circular base, and retaining 25 means for the nipple consisting of a pad having a flexible fabric base, a rubber sheet secured upon said base and adapted for engagement against the base of the nipple, said rubber sheet affording a smooth non- 30 porous surface for contact with the skin of the user, and means connected to the base sheet of said pad for holding the pad in its applied position with relation to the nipple.

35 2. A bougie consisting of a flat circular base having a solid elongated neck centrally projecting therefrom and a hollow compres-

sible nipple formed on the extremity of said neck, said nipple being provided at its apex with a relatively large opening through 40 which the interior of the nipple may be filled with the medicament, and the body wall of the nipple being further provided with a plurality of smaller perforations for the extrusion of the medicament from the nipple 45 upon compression thereof.

3. An apparatus of the character described including a pad, consisting of a fabric base and a rubber sheet secured upon one side of 50 said base, said sheet being provided with a plurality of relatively movable holding tabs, a perforated medicament containing nipple having a base adapted to be engaged by said tabs to detachably hold the nipple in connection with the pad, and means for retaining 55 said pad in its applied position.

4. An apparatus of the character described including a pad consisting of a fabric base sheet and a rubber sheet secured upon the fabric base sheet and having a central opening 60 therein, a perforated medicament containing rubber nipple having a base adapted to be detachably engaged through said opening and held by the rubber sheet in connection with said pad, and means connected to 65 the opposite ends of the pad for retaining the same in its applied position.

In testimony whereof I hereunto affix my signature in the presence of two witnesses.

H. L. BEARD.
